(57) **CLAIM**

We claim the ornamental design for a light fixture, as shown and described.

DESCRIPTION

FIG. 1 is a perspective view from the bottom of the light fixture,

FIG. 2 is an elevational view of the side of the light fixture, FIG. 3 is a top side view of the light fixture; and,

FIG. 4 is a bottom side view of the light fixture.

The broken lines shown on the drawings are for illustrative purposes only and form no part of the claimed design.
